CONVERTIBLE FURNITURE SET

Richard C. Stone, Brooklyn, N. Y.

Application August 10, 1943, Serial No. 498,038

3 Claims. (Cl. 5—18)

This invention relates to a furniture set or unit comprising several pieces which can be assembled in different ways whereby the said set can be adapted for different uses and, when assembled for one use, can be converted for another use. More particularly, the invention relates to a couch or sofa which can be converted into two beds.

An object of this invention is to provide a furniture set which can be so assembled that it either forms a couch or sofa of suitable size and height and of the same appearance as a one-piece structure, or forms two beds of equal and suitable resting surfaces and heights. Further objects are to provide a structure which allows an easy, reliable and quick assemblage of the set in either form, easy and quick conversion from one form into the other, and easy separation into parts for cleaning, moving and other purposes.

Another object is to provide a structure which, in the form of beds, consists of two separate beds which can be placed side by side or in any other relative position whereby the position of the beds can be adapted to the space at disposal or to the individual wishes of the sleepers.

Still other objects are to provide a furniture set of this nature which can be easily cleaned, which substantially consists of wood or non-metallic material, and which comprises pieces each of which has a relatively light weight and forms a solid, separable body without any mechanisms or movable attachments.

Still further objects are to achieve said results with simple and inexpensive means. Still other objects and advantages will appear from the following description of an illustrative embodiment of the invention, from the appended claims and from the accompanying drawings in which:

Fig. 1 shows a spring box forming one piece of the furniture set, seen from the lower side;

Fig. 2 shows the piece shown in Fig. 1, seen from the right side in Fig. 1;

Fig. 3 shows a frame body forming another piece of the set, seen from the upper side;

Fig. 4 shows the piece shown in Fig. 3, seen from the right side in Fig. 3;

Fig. 5 shows the piece shown in Figs. 3 and 4, seen from the lower side in Fig. 3, and a second spring box forming a third piece of the set and inserted in said frame body;

Fig. 6 shows said second spring box seen from the upper side;

Fig. 7 shows the second spring box shown in Figs. 5 and 6, seen from the right side in Fig. 6;

Fig. 8 shows a perspective view of the furniture set assembled in the form of a sofa, the second spring box being partly drawn to the outside;

Fig. 9 shows a perspective view of the furniture set assembled in the form of two separate

beds; and Fig. 10 shows a corner of a modified form of frame body.

Referring to the drawings, numeral 1 indicates a body with a resilient upper surface, for example a spring box which contains inner elastic spring coils mounted on a wooden frame, secured by connecting cords and covered by fabric in conventional manner. A number of wooden projecting ledges 2, 3, 4 are affixed to the lower side of 1 and are so located that they fit into spaces of another piece of the set as will be described later.

Numeral 5 indicates a frame body comprising three vertical walls connected at right angles and being open at the remaining sides. The longer wall 6 is connected to each of the two shorter walls 7 at the touching edge in conventional manner and, in addition, by an obliquely or diagonally positioned slat or board 8 located near the upper edges of the respective walls. Also near said upper edges, a number of wooden ledges 9 are affixed to the wall of the body 5. The ledges 9 and the slats 8 are so positioned that the ledges 2 of the spring box 1 fit between them and that the ledges 4 of 1 with their obliquely cut off ends fit the outer side of the slats 8. All said ledges are so positioned that, when the spring box 1 is laid on the frame body 5, the ledges secure the mutual position of 1 and 5, the ledges of 1 being held in place by the walls, ledges and slats of 5. The shown arrangement makes possible a very convenient manner of putting together or of separating 1 and 5, said manner consisting in turning the body 1 around the upper rim of the wall 6.

A pair of parallel wooden ledges or rails 10 is affixed to the inner side of each wall 7 and forms a slide groove running from the wall 6 to the opposite open side of the body 5. Due to the open structure of the frame body 5 and the easy removal of the spring box 1, the slide groove and all other interior parts of 5 are easy to be cleaned; an important feature of my invention being that the box springs can be readily removed and cleaned; and also the box spring 1 can be easily removed and used as an ordinary bed spring, and the box spring 13 can also be easily removed and used separately in a bed.

The body 5 may be equipped with feet 11. The outside of the walls may be covered by upholstered or plain fabric, or otherwise finished in suitable manner. The body of the walls may be made from wood in conventional manner with reinforced edges.

Another body 12 with a resilient upper surface comprises a spring box 13 which may be similar to the spring box 1 and may be mounted on a wooden frame 14 which slightly projects over the two smaller sides of 13. Feet 15 are affixed to the lower sides of the corners of 14. The

heights of the feet 15 and of the projecting ledges of the frame 14 are so measured that the total height of these parts fits the groove between the ledges of 10 of the piece 5 whereby the body 12 can be pushed into the body 5 with the feet of 12 sliding on the lower ledges 10, the total size of the body 12 being sufficiently smaller than the size of the frame body 5. In the same way, the body 12 can be withdrawn. The fact that the sliding body 12 touches said ledges only with the feet and not at the entire length of the ledges facilitates said operations, the friction and the possibility of jamming being reduced.

The furniture set further comprises a resilient piece or mattress 16 having the same surface area as the spring box 1 and a height which exceeds the height of the body 1 as much as the height of the frame body 5 exceeds the height of the body 12 whereby the height of 12 and 16 together is equal to the height of 5 and 1 together.

Generally, that is when cleaning or other purposes do not require separation, the spring box 1 rests permanently on the frame body 5, the mutual position being secured as described before. In order to form a couch or a sofa, the spring box body 12 is completely pushed into the frame body 5 in the manner described before and the mattress 16 is placed on top of 1. The thus formed settee or couch may be placed against a wall of the room either with the open side of the frame 5 against the wall, whereby the opening is concealed, or with the open side opposite to the wall, whereby no movement of the bodies 1 and 5 is necessary for the conversion of the furniture set. Cushions 17 may be placed on the mattress 16 and may form a back at the side of the wall of the room.

In order to form beds, the spring box body 12 is taken out of the frame body 5 and set down at any place desired. Then, the mattress 16 is removed from the spring box 1 and placed on top of the spring box 12 whereby two independent beds of equal heights and resting surfaces are made.

A modification of my invention, allowing for reduction of transportation and storage space, is similar to the embodiment described before, except a detail of the frame body which is shown in Fig. 10. In this modification, the wall 26 corresponding to the wall 6 of the first embodiment, is not rigidly connected to the two side walls 27 corresponding to the walls 7 of the first embodiment, but 26 and 27 are connected by hinges 21. The diagonal slats 8 are replaced by bars, each of which consists of two parts 28 and 29 which are connected by a hinge 22. The outer end of bar 28 is connected to the wall 26 by a hinge 23, and the outer end of the bar 29 is connected to the respective wall 27 by a hinge 24. This structure allows to fold the side walls 27 into a position parallel to the wall 26.

In some cases the box spring 13 may be contained or held in the body 5 without use of the ledges 10 and the slats; also the box spring 1 can be made without 2, 3 and 4.

In this specification and claims the terms "box-spring" and "spring-box" are used interchangeably.

It should be understood that the invention is not confined to the particular forms and uses shown and described and that the invention may be carried out in modified ways without departing from the spirit of the invention, as it is

obvious that the embodiment shown and described is only one of the many that may be employed to attain the objects of the invention.

Having described the nature of the invention and how it operates, what I claim and desire to secure by Letter Patent is:

1. A convertible furniture set comprising a frame body having a vertical wall and two other vertical walls extending horizontally at right angles from said first wall, said frame body being open at its upper side and at the side opposite to said first wall and having two pairs of spaced ledges, one of said pairs being affixed to the inner side of each of said other walls and running from said first wall to the opposite open side; a spring box removably covering the upper open side of said frame body and having projections affixed to its lower side which fit into the upper opening of said frame body; and another spring box having outer measures slightly smaller than said frame body, and opposite lateral projections fitting into the spaces between said ledges whereby said other spring box can be removably inserted in said frame body.

2. A convertible furniture set comprising a frame body having a vertical wall and two other vertical walls extending horizontally at right angles from said first wall, said frame body being open at its upper side and at the side opposite to said first wall, having two pairs of spaced ledges, one of said pairs being affixed to the inner side of each of said other walls and running from said first wall to the opposite open side, having a plurality of spaced ledges affixed to the inner side of said first wall near the upper rim thereof and having two slats, each connecting one of said other walls with said first wall diagonally near the upper rim of said frame body; a spring box removably covering the upper open side of said frame body and having projecting ledges affixed to its lower side, some of said ledges fitting into the spaces between said ledges near the upper rim of said frame body and some other of said ledges having obliquely cut ends fitting the obliquely positioned sides of said diagonal slats; and another spring box having outer measures slightly smaller than said frame body, and opposite lateral projections fitting into the spaces between said ledges arranged in pairs.

3. A convertible furniture set comprising a frame body having a vertical wall and two other vertical walls extending horizontally at right angles from said first wall, said frame body being open at its upper side and at the side opposite to said first wall and having two pairs of spaced ledges, one of said pairs being affixed to the inner side of each of said other walls and running from said first wall to the opposite open side; a spring box removably covering the upper side of said frame body and having projecting ledges affixed to its lower side, said latter ledges fitting into the upper opening of said frame body; another spring box having outer measures slightly smaller than said frame body and lateral projections comprising feet, said lateral projections fitting into the spaces between said ledges arranged in pairs; and a mattress adapted to be placed on either of said two spring boxes and having a height exceeding the height of said first spring box as much as the height of said frame body exceeds the height of said second spring box.

RICHARD C. STONE.
